UNITED STATES PATENT OFFICE

146,517

DESIGN FOR AN ELECTRIC IRON

Hendrik Albert Nieboer, London, England

Application February 19, 1946, Serial No. 126,702
In Great Britain October 16, 1945

Term of patent 7 years

(Cl. D49—6)

To all whom it may concern:

Be it known that I, Hendrik Albert Nieboer, a British subject and a resident of London, England, have invented a new, original, and ornamental Design for an Electric Iron, of which the following is a specification, reference being had to the accompanying drawing, forming part thereof.

Referring to the drawing,

Figure 1 is a perspective view of an electric iron, showing my new design, and
Figure 2 is a side view thereof.

I claim:

The ornamental design for an electric iron, substantially as shown.

HENDRIK ALBERT NIEBOER.
